UNITED STATES PATENT OFFICE.

JOHN J. DONOVAN, OF WATERBURY, CONNECTICUT.

SHAVING MIRROR.

Application filed July 15, 1926. Serial No. 122,546.

Fig. 1 is an underside view of a shaving-mirror construed in accordance with my invention;

Fig. 2 is a face view of the same; and
5 Fig. 3 is a sectional view on the line 3—3 of Fig. 2.

This invention relates to improvement in shaving-mirrors. In shaving-mirrors, it is desirable that lights should be provided 10 and that these lights should be at opposite sides and in fixed relation to the mirror. The object of this invention is to provide a shaving-mirror with a fixed light at each side and so arranged that the wires to these 15 lights shall be properly housed, and the invention consists in the construction as hereinafter described and particularly recited in the claim.

In carrying out my invention, I employ a 20 mirror 5 of suitable size and form, and this mirror is provided with a metal backing 6 formed with fingers 7 to turn over the edge of the mirror, whereby the backing is held in place. Secured to the backing is a 25 bracket-plate 8 by which the mirror is suspended. On each side is a lamp-casing 9 forming reflectors and providing supports for electric lamp-sockets 10, these reflectors being formed integral with the backing or 30 formed separately therefrom and attached

thereto. The backing is formed with two outwardly-struck grooves 11 and 12 extending from the lower corners to a point adjacent to the center of the upper edge, and these grooves form channels for wires 13 and 14 which extend to the lamps 10. The wires 13 and 14 are connected through a switch 15 of ordinary construction mounted on the bracket 8 and having an operating-button 16 with circuit-wires 17 and 18. The wires 40 from the switch to the lamps are thus housed and are protected against displacement, and the switch is arranged in a convenient position for operation.

I claim:

A shaving-mirror, comprising a mirror-glass, a metal backing secured thereto, reflectors secured to opposite sides of the mirror, a lamp mounted in each reflector, said backing formed with outwardly-struck 50 grooves extending from the lower corners upward to a point near the center of the upper edge, a bracket attached to the backing for the suspension thereof, a switch mounted in said bracket, and electric wires 55 extending from said switch through said channels to said lamps.

In testimony whereof, I have signed this specification.

JOHN J. DONOVAN.
